UNITED STATES PATENT OFFICE.

GILBERT J. DICKSON, OF ALBANY, NEW YORK.

TRANSOM-LIFTER.

SPECIFICATION forming part of Letters Patent No. 398,240, dated February 19, 1889.

Application filed September 18, 1888. Serial No. 285,729. (No model.)

To all whom it may concern:

Be it known that I, GILBERT J. DICKSON, of the city and county of Albany, in the State of New York, have invented new and useful 5 Improvements in Transom-Adjusters, of which the following is a specification.

My invention relates to improvements on that class of appliances by which a transom-light can be adjusted and secured at any 10 point in the path of its movement; and the object of my invention is to provide a simple and reliable appliance for accomplishing the above purpose. I attain this object by the mechanism illustrated in the accompanying 15 drawings, which are herein referred to, and form part of this specification, and in which—

Figure 1 is a front elevation of my transom-adjuster applied to a transom-light with the latter in its closed position. Fig. 2 is a side 20 elevation of the same with part of the frame of the transom-light broken away to expose hidden parts of the adjuster. Fig. 3 is a like elevation showing the transom-light in an open position. Fig. 4 is an enlarged horizontal 25 section, at the line X X on Fig. 1, of the operating-rod and a bracket for guiding the same, the upper lug of said bracket being removed to show the locking device; and Fig. 30 5 is a front elevation of part of said operating-rod and the bracket and locking device for same.

As represented in the drawings, A designates a door-casing provided with a transom-light, B, which is hinged at its lower edge to 35 the said casing. All of said parts are of an old and well-known construction.

C is an operating-rod whose upper end is articulated to a joint-rod, D, having at its lower end a block, 1, which is fitted to reciprocate on a guide, E, that is secured to the face of the door-casing A. The upper end of the joint-rod D is fitted to slide in a slotted bracket, F, that is secured to the face of the transom-light B. Said joint-rod is provided 45 with a pivot-pin, 2, which engages in the outer end of a swinging arm, G, whose inner end is pivoted, as at 3, to that part of the door-casing A in which the transom-light B is contained.

50 H is a bracket, that is secured to the face of the door-casing A for the purpose of guiding the lower part of the operating-rod C.

Said bracket is preferably made with two horizontal lugs, 4, which are arranged parallel to each other, and are provided with suitable openings in which said operating-rod is fitted to slide freely. A locking-piece, I, is fitted to said bracket, and it may be arranged so as to work between the lugs 4, or on either of them, and it is provided with a slotted opening, 5, which has one end sufficiently large to permit the operating-rod C to slide freely therethrough, and the remainder is reduced in width to form a lip, 6, which is fitted to engage in either one of a series of notches, 7, 65 which are formed in said operating-rod for the purpose of securing the latter in a position corresponding to any one of said notches; and it will readily be seen that any preferred number of intermediate notches can be made 70 between the lowest and highest notches, the intermediate notches serving to secure the transom-light in a partially-opened position at any point between the extremes of the movements of said light. 75

My transom-adjuster operates in the following manner: The transom-light B being in its closed position, as shown in Figs. 1 and 2, with the operating-rod C locked in a corresponding position, said transom-light is opened by 80 first moving the locking-piece I into a position indicated by dotted lines in Fig. 4, where said rod will be free to slide in the bracket H. By a downward movement of the operating-rod the joint-bar D will be drawn in a corresponding direction, and thereby the outer end of the swinging arm G is forced to move outwardly, so as to produce an opening movement of the transom-light B. The closing movement of the latter is effected by moving 85 the operating-rod C upwardly, thereby restoring the parts to their positions shown in Figs. 1 and 2. When preferred, the inner end of the swinging arm G can be pivoted to the casing A at a point that will be above the 90 pivot-pin 2, and this change can be made without any material alteration of the construction of the parts herein shown and described; but the opening movement of the transom-light B will then be effected by an upward 95 movement of the operating-rod C, and the closing movement of said transom-light will be effected by a downward movement of said operating-rod. In either arrangement the op- 100

erating-rod C can be locked at any point of its movement by the locking device herein shown and described, or by one that is substantially the same.

5 I claim as my invention—

1. In a transom-adjuster, the combination of an operating-rod whose upper end is fitted to slide on a guide that is secured to the door-casing, a joint-bar having its lower end articulated to the upper end of said operating-rod, and its opposite end being fitted to engage in a slotted bracket which is secured to the transom-light, said joint-bar being provided with a pivot-pin arranged intermediately between its ends, and a swinging arm having one end pivoted to a fixed point on the door-casing and the opposite end pivoted to the pivot-pin of said joint-bar, as and for the purpose herein specified.
- 10
- 15

2. In a transom-adjuster, the combination 20 of an operating-rod having a series of notches formed therein, a bracket which guides said operating-rod and is provided with a locking-piece which moves in a direction transversely to the movement of said operating-rod, said 25 locking-piece being provided with a slotted opening which has at one end an enlargement through which the body of said operating-rod can slide freely, and at the opposite end a lip which is fitted to engage in any one 30 of said notches, as and for the purpose herein specified.

GILBERT J. DICKSON.
